BABY CRIB

Max Klopfer, Woodside, and Max Rothschild,
New York, N. Y.

Application June 23, 1939, Serial No. 280,744

4 Claims. (Cl. 5—93)

This invention relates to baby cribs, and more particularly to cribs that are foldable to provide portability and which are formed of wood, metal or any other suitable material. This application is a continuation in part of our application, Ser. No. 273,158, filed May 12, 1939.

Among the features of the invention are:

A crib made up of sections comprising vertical corner posts, cross-bars at the top and at the bottom connecting said posts, and vertical posts mounted on the cross-bars to provide barriers against a baby crawling through between them; having flat cross-pieces supportable in a plurality of vertical positions at opposite ends so that these flat cross-pieces can be placed in different vertical positions to provide a bed, floor, seats, or tables; having four or more flat cross-pieces; having flat cross-pieces formed in symmetrical pairs; having means on the cross-pieces for securing the side sections in exact spaced-apart relationship; having means on the cross-pieces for holding the side sections against outward displacement; having two symmetrical parts, each part comprising an end section and two side sections, and means for locking the open ends of the parts together to form a rectangular pen; each part having hinges between each end and the adjacent side sections, and so constructed that the three sections can be folded together in parallel relationship; having the flat cross-pieces notched at the corners for mounting on the vertical posts; having the vertical posts and an intermediate vertical post in each side section notched for securing the cross-pieces in a plurality of vertical positions and so securing the cross-pieces in the vertical position with the cross-pieces easily insertable in and removable from their supports; having the end cross-pieces notched at the corners and also the intermediate cross-pieces notched at the corners so that the flat cross-pieces can entirely cover the cross-sectional space within the crib to provide a floor or to provide a bed in either of which the cross-pieces are in the same plane, and to provide a table formed of the two central cross-pieces with two cross-piece seats, one near each end of the pen and set in a lower plane. The table may be divided to form two chairs with a table in front of each seat. A mattress may be used for the bed which is divisible into two equal parts so that when the pen is separated, the mattress may be separated to provide cushions for each of two chairs, each of which has two cross-pieces in the same plane.

Other features of the invention will appear as the description proceeds.

Reference is made to the drawings in which,

Fig. 1 is a perspective view showing the pen made up as a bed. 5

Fig. 2 is a plan view showing the device made up as a play pen with a floor. 10

Fig. 3 is a view taken from the left end of Fig. 1.

Fig. 4 is an elevation looking in the direction of the arrows and taken on the line 4—4 of Fig. 2. 15

Fig. 5 is a view taken on the line 5—5 of Fig. 2, and looking in the direction of the arrows. 20

Fig. 6 is a perspective view showing the device in the folded portable position. 25

A vertical post 10 and a vertical post 11 are connected by a horizontal cross-bar 12 at the top and a horizontal cross-bar 13 at the bottom. A vertical bar 14, a vertical bar 15, a vertical intermediate post 16, and a vertical bar 17 are mounted at the top in the cross-bar 12 and at the bottom in the cross-bar 13 and are so spaced from each other and from the vertical end posts, that a baby can not pass thru the side as formed. This side section is connected by hinges 18 with a corner post 19 which is extended in cross-section in a rectangle about twice the size of the post 11 in cross-section. The left end has a vertical post 19 at the opposite corner, and a cross-bar 20 at the top, and a cross-bar 21 at the bottom connect the vertical posts 18 and 19. Vertical bars 22, 23, 24, 25, and 26 are mounted at the top in the cross-bar 20 and at the bottom in the cross-bar 21, and are so spaced from each other and the end posts, that a baby cannot pass thru. A vertical post 27 is connected by hinges 28 with the vertical post 19 and is connected with the vertical post 29 by means of a cross-bar 30 at the top and a cross-bar 31 at the bottom. Vertical bars 32, 33, a vertical intermediate post 34, and vertical bars 35, and 36 are connected at the top with the cross-bar 30 and at the bottom with the cross-bar 31. The spacing of these vertical bars and vertical posts is such that a baby can not pass thru. A flat cross-piece 37 and a flat cross-piece 38 support a cushion 39 thereon and substantially fill the entire area of the part formed by the end piece and the two adjacent sides in the open position. At either side on the front edge of the flat cross-piece 37 is a transversely extending pin 40 which engages in recesses 42 formed in the inner wall of notches 41 formed in the vertical posts 10 and 29. These pins 40 and recesses 42 prevent the sides from spreading apart when the part above described is used as a chair or separably. Notches 41 are also 30
35
40
45
50
55

formed symmetrically on the side wall of the posts 11 and 27 so there are a plurality of supports formed for supporting the flat cross-pieces 37 and 38 which cooperate with supports 43 and 45 formed on the intermediate posts 16 and 34 in the same plane as the notches in the posts 10, 11, 27, and 29. The corners of the cross-pieces 37 and 38 have right-angled cornered cuts therein for fitting on the posts 10, 16, 11, 27, 34 and 29 so that their ends directly engage the vertical bars 14, 15, 17, 32, 33, 35, and 36 and when assembled the flat pieces 37 and 38 make one unitary support adjoining at the edges. The other part of the pen or crib is similar to the part just described. The post 50 is similar to the post 10, the post 51 to the post 11, the cross-bar 52 to the cross-bar 12, the cross-bar 53 to the cross-bar 13, vertical bars 54 and 55, the vertical intermediate post 56 and the vertical bar 57 are similar to the vertical bars 14, 15, the vertical post 16, and the vertical bar 17, and together form a similar side piece. The post 51 is mounted by means of hinges 97 on the post 58 which is similar to the post 18 and cross-bars 60 and 61 are similar to the cross-bars 20 and 21 at the opposite end and mount vertical bars 62, 63, 64, 65, and 66 which are similar to the vertical bars 22, 23, 24, 25, and 26. The cross-bars 60 and 61 connect the post 58 with the post 59. A vertical post 67 is similar to the post 27 and is hinged at 68 to the post 59. A post 69 is similar to the post 29 and is connected with the post 67 by cross-bars 70 and 71 which are similar to the cross-bars 30 and 31. Vertical bars 72, 73, the intermediate vertical post 74, and vertical bars 75 and 76 are mounted in the cross-bars 70 and 71 and are similar to the vertical bars 32, 33, the vertical side member 34, and the vertical bars 35 and 36. The last-described side section, when folded over on the hinge 68, lies parallel with the end section, as does the vertical side section defined by the posts 27 and 29 which, turned on its hinges 28, lies adjacent to the opposite end. When the side section having posts 50 and 51 is folded on its hinges 97 it lies over the side section formed by posts 67 and 69 to form three parallel sections which are flat and easily portable. Similarly when the side formed by the vertical posts 10 and 11 is folded over the side formed by the posts 27 and 29, three parallel sections make up the other part so that the entire crib comprises these two flat folded sections which may be placed on top of each other, with the flat cross-pieces 37, 38, 77, and 78 interposed between, so that all can be tied up in one portable bundle. Pins 40 can be mounted on the front edge of cross-piece 77 similar to the pins 40 and may enter recesses 42 formed in the notches 41 to cut on the inside wall of the posts 50 and 69 to prevent them from spreading apart when the cross-piece 77 is in place in the notches 41 and 45. The cross-pieces 77 and 78 cover the entire part formed by the right side and together with the cross-pieces 37 and 38 entirely cover the inside area of the pen so that they provide a complete floor for the pen or complete support for the bed. The cross-pieces 37, 38, 77, and 78 are easily swung into or out of position on an axial line thru their opposite edges by means of curved cutaways 44 and 46 over the seats of the notches 43 and 45. The posts 29 and 50 may have suitable inter-engaging locking members 48 and 49 and the dowel 80, as well as the posts 10 and 69, so that the two similar parts may be locked together on both sides, at the center. It is clear that the

cross-pieces can be raised or lowered and set in any one of a set of notches 41, 43 and 45 in the same horizontal plane or the cross-piece 37 may be set at a higher position and the cross-piece 38 in a lower position to form a table with a seat at the rear and at the end of the pen. Similarly the cross-piece 77 may be set in a higher position and the cross-piece 78 may be set in a lower position to form a similar combined table or seat. It is also obvious that the two similar parts of the crib may be divided at the center, by unlocking the inter-engaging members 48 and 49, to form two cushion chairs, which can be set in any desired position.

Having shown and described one embodiment of our invention and realizing that, in view of our disclosure, many changes in materials and details of construction will readily occur to those skilled in the art, we do not limit ourselves to the exact disclosure.

We claim:

1. A baby crib made up of sections, comprising six sections, these sections being formed in two symmetrical parts of three sections each, each symmetrical part having an end section and two side sections vertically hinged on opposite posts of the end section, each section having two end vertical posts, the posts of each end section being hinged to the adjacent posts of each side section to form joint corner posts, horizontal cross-bars mounted on the end posts of each side section, an intermediate vertical post mounted on said cross-bars, other vertical posts mounted on said cross-bars between the end posts, all so spaced from each other as to prevent a baby passing thru between them, the joint corner posts and the opposite end post of each side section and an intermediate vertical post having means in the same plane for supporting flat cross-pieces thereon, said supporting means on said intermediate vertical post on opposite sides being so constructed that the flat cross-pieces are tiltable upwardly, and flat cross-pieces supportable on said supporting means, the supporting means being so constructed that the cross-pieces are insertable in and removable from each section.

2. A baby crib comprising two symmetrical parts, joinable together to form the crib, each part having an end section and two side sections, the side sections hinged to the end sections and comprising end vertical posts, horizontal cross-bars between the end posts and connecting with the posts at the top and bottom thereof, a vertical post intermediate the end posts and mounted on the cross-bars, a plurality of notches on the end posts and a plurality of notches on the opposite sides of the vertical intermediate post, the notches on the end posts and on the vertical intermediate post being in the same horizontal planes, the vertical intermediate post having cutaway portions above the notches so that flat cross-pieces can be swung vertically into and out of position in the notches, and flat cross-pieces supportable in the notches in the vertical intermediate post and in the adjacent end posts in a plurality of vertical positions.

3. A baby crib having two parts, joinable together to form the crib, each part comprising an end section and two side sections, the side sections being hinged to the adjacent end sections, the end sections comprising two vertical end posts, cross-bars connecting the posts at the top and bottom and vertical intermediate posts mounted on the cross-bars, each side section comprising

- two vertical end posts and cross-bars connecting said posts at the top and bottom, a vertical intermediate post mounted on the cross-bars, flat cross-pieces supportable between the two sides of 5 notches on the vertical intermediate post and on each part and having angled cutaway corners, the end posts for engaging the corners of the cross-pieces, one of a pair of notches on opposite sides being cutaway at the top to provide for the 10 vertical positioning and removal of the flat cross-piece therefrom, and means mounted near each end on one of the cross-pieces and engageable with the vertical end post for securing said side sections against spreading apart.
- 15 4. A baby crib having two parts, joinable together to form the crib, each part comprising an end section and two side sections, the side sections being hinged to the adjacent end sections, the end sections comprising two vertical end posts, horizontal cross-bars connecting the posts at the 15 top and bottom and vertical intermediate posts mounted on the cross-bars, each side section comprising two vertical end posts and horizontal cross-bars connecting said end posts at the top and bottom, a vertical post mounted on the cross-bars intermediate the end posts, flat cross-pieces supportable between the two sides of each part and having cutaway corners, notches on the vertical intermediate post and on the end posts for engaging the corners of the cross-pieces, one of each pair of notches being cutaway at the top to provide for the vertical positioning and removal of the cross-piece thereon, and pins mounted near each end of one of the flat cross-pieces and engageable in sockets in the adjacent end posts for securing the side sections against outward movement away from each other.

MAX KLOPFER.

MAX ROTHSCHILD.
